UNITED STATES PATENT OFFICE.

BROCK CAMERON, OF GUELPH, CANADA, ASSIGNOR OF ONE-HALF TO
WILLIAM BROCK KER, OF SAME PLACE.

DESIGN FOR AN INK-BOTTLE.

SPECIFICATION forming part of Design No. 28,633, dated May 17, 1898.

Application filed March 28, 1898. Serial No. 675,502. Term of patent 14 years.

To all whom it may concern:

Be it known that I, BROCK CAMERON, a subject of the Queen of Great Britain, residing at the city of Guelph, in the county of Wellington and Province of Ontario, Canada, have invented and produced a new and original Design for Ink-Bottles, of which the following is a specification, reference being had to the accompanying drawings, forming part thereof.

Figure 1 is a vertical section of my ink-bottle. Fig. 2 is a perspective view of the same.

A is the body of the bottle, which is rectangular in elevation, as shown.

The bottom B of the bottle is raised so as to form triangular spaces between itself and the sides of the bottle.

From one side of the body of the bottle pro-

jects the spout or neck C, starting at the extreme lower edge.

The essential feature of my design consists in the body, substantially rectangular in section or side elevation, and in the neck or spout, extending diagonally upward from the lower portion of one of the sides.

Having described my invention, what I claim as new, and desire to secure by Letters Patent, is—

The design for an ink-bottle, substantially as herein shown and described.

Guelph, January 31, 1898.

BROCK CAMERON.
